(57) **CLAIM**

The ornamental design for a switch apparatus, as shown and described.

DESCRIPTION

FIG. 1 is an upper left perspective view of the switch apparatus;

FIG. 2 is an upper right perspective view of the switch apparatus;

FIG. 3 is a lower right perspective view of the switch apparatus;

FIG. 4 is a lower left perspective view of the switch apparatus;

FIG. 5 is an enlargement of an enclosed portion of FIG. 1 and additionally depicts an alternative position of a component of the switch apparatus;

FIG. 6 is an enlargement of an enclosed portion of FIG. 3 and additionally depicts an alternative position of another component of the switch apparatus;

FIG. 7 is a left side elevational view of the switch apparatus;

FIG. 8 is a front elevational view of the switch apparatus;

FIG. 9 is a right side elevational view of the switch apparatus;

FIG. 10 is a rear elevational view of the switch apparatus;

FIG. 11 is a top plan view of the switch apparatus; and,

FIG. 12 is a bottom plan view of the switch apparatus.

The long-dashed lines depicted in FIGS. 1 and 3 are only for illustration, by enclosing therein, of the portions of FIGS. 1 and 3 that are depicted in an enlarged fashion in FIGS. 5 and 6, respectively, and form no part of the claimed design. The medium-dashed lines are for illustration of environmental subject matter only and form no part of the claimed design. The short-dashed lines shown in FIGS. 5 and 6 are for illustration of exemplary alternative positions of components of the switch apparatus only and form no part of the claimed design.
